GOLF SHOE

Elliott H. Feinberg, New York, N. Y.

Application March 21, 1940, Serial No. 325,217

7 Claims. (Cl. 36—1)

This invention relates generally to footwear and more particularly to sport shoes having spikes or cleats on the soles and heels and the combination therewith of an overshoe of novel construction.

Among the objects of the present invention is the provision of a combination shoe and overshoe which permits of adequate spike or cleat action whether or not the overshoe is being worn.

It is well known that many sports require the use of shoes by the player which will enable him to get a good stance or grip on the ground, this is particularly true of the game of golf. When playing golf, frequently the grounds are wet, as for example during the early morning when dew is prevalent, or during or after rain. When ordinary golf shoes, usually composed of leather, are worn during such playing conditions, the shoes become impregnated with water and are then uncomfortable and unhealthful. While practically all players prefer to use spiked shoes, under damp and muddy ground conditions, they are forced to abandon their spiked shoes and to use ordinary unspiked shoes with well known "rubbers" or overshoes. In doing so the advantage of having a good grip on the ground is lost, and other disadvantages also arise. For example when heavy dew is encountered when playing early in the morning, it is necessary to wear overshoes. Later in the morning the sun comes out and dries the dew, it is then very desirable to wear spiked shoes. The dew may dry when the player is far from the clubhouse, and it is necessary to return to the clubhouse and change shoes or to carry an extra pair of shoes along, an annoying burden.

In accordance with the present invention, the player may start out on the course early in the morning while the ground is very wet with dew. He wears a combination shoe and overshoe which allows the spikes to project downwardly through the overshoe and to properly grip the ground. Later in the day when the ground is dried by the sun, he need only remove the light weight overshoes, place them in his golf bag, and continue playing in his regular spike shoes which are dry and comfortable.

Another object of the present invention lies in the provision of an overshoe having the above described advantages yet which may be readily adapted for use with golf shoes of known spiked construction and presently in use. This means that the golfer may either purchase an outfit of spiked shoes and overshoes designed to be used therewith, or if he already has spiked shoes he

may have a pair of applicant's novel overshoes fitted to these shoes.

Another object herein lies in the provision of a spiked shoe overshoe which is light in weight, durable, and which may be manufactured at low cost so that the same may have wide commercial distribution.

Another object herein lies in the provision of a spiked shoe overshoe which is easily put on or taken off and yet which will when in use prevent undesirable moisture from reaching the shoe.

These objects and other incidental ends and advantages will more fully appear in the progress of this disclosure and be pointed out in the appended claims.

In the drawings forming a material part of this disclosure, corresponding parts are designated by similar reference characters throughout the different views of each embodiment.

Figure 1 is a view in perspective showing a first embodiment of the invention. In this view the shoe is shown as inserted within the overshoe.

Figure 2 is a perspective view of Figure 1, but taken from a higher position.

Figure 3 is an enlarged bottom plan view of the overshoe seen in Figure 1.

Figure 4 is a schematic sectional view of Figure 3 as seen from the plane 4—4 thereon.

Figure 5 is an enlarged fragmentary sectional view partly in elevation as seen from the plane 5—5 on Figure 3.

Figure 6 is a view taken similarly to Figure 2 but shows a second embodiment of the invention.

Figure 7 is a view taken similarly to Figure 5, but shows a second embodiment of the invention.

Figure 8 is a view taken similarly to Figure 1 but shows a third embodiment of the invention.

Figure 9 is taken similarly to Figures 5 and 7 but shows a third embodiment of the invention.

Turning now to the first embodiment of the invention illustrated in Figures 1 to 5 inclusive, the combination spiked golf shoe and overshoe is generally indicated by numeral 10.

The golf shoe 11 may be of any desired construction well known in the art, so that a detailed description thereof is not deemed necessary. The bottom portion of the shoe 11 is provided with a plurality of spikes 12. The spikes 12 may either be permanently attached to the sole 13 of the shoe, and the heel, or the spikes 12 may be detachably attached to the sole and heel in any suitable manner known in the prior art. One

manner is illustrated in the drawings and seen in detail in Figure 5, in which the sole 13 is provided with an internally threaded sleeve 14, covered by an insole 15. The spike 12 includes a frusto-conical point 16, an annular flange 17, and a threaded shank 18. The flange 17 includes indentations 19 and 20 which may be engaged by a tool having a similar configuration for the purpose of screwing in or screwing out the spike. The spikes 12 are arranged over the bottom portions of the shoe 11 in any desirable configuration or arrangement, several standard patterns have been adopted and are now in use by the large sport shoe manufacturers.

The overshoe 21 may be of any known and acceptable basic construction. Since, when in use a considerable amount of the wear is taken by the spike points 16, it is desirable that the overshoe be of relatively thin construction. This permits ample downward projection of the spike points 16, and also reduces the overall weight of the overshoe, which is an advantage, since the overshoe is principally employed for auxiliary service. The overshoe 21 may be of all gum or rubber construction or it may be made of laminations of rubber and textile material.

The lower portions of the overshoe, namely the sole portion 22 and the heel portion 23 are provided with a plurality of orifices 24. The orifices 24 may be merely punched out apertures in the sole portion 22 and the heel portion 23, but then a much more satisfactory device results when the orifices 24 have the overshoe portions bordering the same provided with reinforcements 25 and 26, which may be in the form of eyelets, or small grommets and rings, or tubular rivets as shown. As seen in Figures 4 and 5 the reinforcement 25 includes a cylindrical portion 27, and upper and lower peripheral flanges 28 and 29 respectively. The diameter of the inside of the cylindrical portion 27 is such that the point 16 may pass freely therethrough, while the flange 28 may engage the flange 17. As seen in Figure 5, the point 16 extends below or outwardly of the flange 29 a distance sufficient to properly engage the ground when the combined shoe and overshoe are worn.

The vamp portion 30 of the overshoe 21 is provided with a known slide fastening device 31 which when opened facilitates the engagement and disengagement of the overshoe 21 with the shoe 11, since certain lateral movement of the overshoe in this operation is desirable, and the lateral movement is not possible until the reinforcements are disengaged from the spike points.

The reinforcements 25 and 26 may be of metal, or any other suitable material.

In the second embodiment of the invention, illustrated in Figures 6 and 7, parts corresponding to the first embodiment are given corresponding reference characters with the addition of prime marks.

Principal differences over the first embodiment lie in vamp construction and the engagement of the orificed portions of the sole and heel of the overshoe with the spike points which are of a different construction.

The vamp portion 30' has an open area indicated by numeral 32, which is bridged by an adjustable snap fastening strap 33.

The point 16' is provided with an annular groove 34, which is therefore of reduced diameter with relation to the normal spike construction. The orifices 24' have the edges thereof provided with reinforcements 25' which are of

a resilient nature. Where the overshoe 21' is composed of rubber, the reinforcements 25' may be an integral rubber bead, rib, or rim, as shown in Figure 7. Where desired, however, the reinforcement 25' may be made of metal in a spring form, or may be a metal eyelet of resilient construction. When the overshoe 21' is put on, the points 16' are pushed into the reinforcements 25' which are expanded by the cone shape of the point 16', but which contract into the groove 34 providing a snap action and promoting a watertight joint therat.

In the third embodiment of the invention, illustrated in Figures 8 and 9, parts corresponding to the first embodiment are given corresponding reference characters with the addition of double prime marks.

Principal differences over the first embodiment and second embodiment lie in the vamp construction, the omission of the heel, and the use of a heel strap on the overshoe. Also the method of fastening the overshoe to the shoe by means of the spikes.

The orifices 24'' are provided with reinforcements 25''. The shank 18'' is lengthened so that the shank 18'' is passed through the reinforcement 25'' as contrasted with the other embodiments in which the point is passed through the reinforcements. When the spike is screwed into place, the overshoe sole portion 22'' is compressed between the shoe sole portion 13'' and the flange 17''. This means that the overshoe is held onto the shoe by the spikes, together with the heel strap 40, which may or may not be required.

It may thus be seen that I have disclosed a novel combination golf shoe and overshoe which has a high degree of utility since the spikes are effective whether or not the overshoe is worn.

While the invention finds good utilization in golf shoes, obviously it may be used in other ways with equal effectiveness. Examples of this are shoes for all kinds of sports, hiking, shoes for walking on ice or other slippery surfaces, where the protection of an overshoe is desired.

I wish it to be understood that I do not desire to be limited to the exact details of construction shown and described, for obvious modifications will occur to a person skilled in the art.

I claim:

1. The combination with a shoe having a plurality of spikes projecting therefrom, the downwardly projecting portions of said spikes being of a certain length; of an overshoe disengageably engageable with said shoe, said overshoe having a lower portion of a thickness substantially less than the length of said spikes, the said lower portion of the overshoe having a plurality of orifices disposed therein, the orifices permitting penetration therethrough and projection therebelow of the said spikes, whereby the shoe is protected by the overshoe and the spikes may grip a surface which the shoe and overshoe overlie.

2. A golf overshoe for shoes having spikes, comprising: a sole portion having a plurality of orifices therein through which the spikes penetrate and project downwardly below the lowermost surface of said sole portion, the thickness of the sole portion being substantially less than the length of the spikes.

3. The combination with a shoe having a plurality of spikes projecting therefrom, the downwardly projecting portions of said spikes being of a certain length; of an overshoe disengageably engageable with said shoe, said overshoe having

a lower portion of a thickness substantially less than the length of said spikes, the said lower portion of the overshoe having a plurality of reinforcing means associated with the edges of the overshoe bordering said orifices, the reinforcing means permitting penetration therethrough and projection therebelow of the said spikes, whereby the shoe is protected by the overshoe and the spikes may grip a surface which the shoe and overshoe overlie.

4. The combination with a shoe having a plurality of spikes projecting therefrom, the downwardly projecting portions of said spikes being of a certain length; of an overshoe disengageably engageable with said shoe, said overshoe having a lower portion of a thickness substantially less than the length of said spikes, the said lower portion of the overshoe having a plurality of reinforcing means including a thickened annular rim associated with the edges of the overshoe bordering said orifices, the reinforcing means permitting penetration therethrough and projection therebelow of the said spikes, whereby the shoe is protected by the overshoe and the spikes may grip a surface which the shoe and overshoe overlie.

5. The combination with a shoe having a plurality of spikes projecting therefrom, the downwardly projecting portions of said spikes being of a certain length; of an overshoe disengageably engageable with said shoe, said overshoe having a lower portion of a thickness substantially less than the length of said spikes, the said lower portion of the overshoe having a plurality of reinforcing means including an eyelet, associated with the edges of the overshoe bordering said orifices, the reinforcing means permitting penetration therethrough and projection therebelow of

the said spikes, whereby the shoe is protected by the overshoe and the spikes may grip a surface which the shoe and overshoe overlie.

6. A combination shoe and overshoe comprising: a shoe having a plurality of spikes projecting therefrom, the downwardly projecting portions of said spikes being of a certain length; said spikes each having an annular groove of reduced diameter; an overshoe disengageably engageable with said shoe, said overshoe having a lower portion of a thickness substantially less than the length of said spikes; the lower portion of the overshoe having a plurality of orifices disposed therein, the material of the overshoe bordering said orifices being resilient; said orifices permitting the penetration therethrough and projection therebelow of the said spikes, the edges of said overshoe bordering the orifices acting to engage the grooves in said spikes, promoting a water tight joint thereat, whereby the shoe is protected by the overshoe and the spikes may grip a surface which the shoe may rest upon.

7. A combination shoe and overshoe comprising: a shoe having a plurality of spikes projecting therefrom, the downwardly projecting portions of said spikes being of a certain length; an overshoe disengageably engageable with said shoe, said overshoe having a lower portion of a thickness less than the length of said spikes, the lower portion of the overshoe having a plurality of orifices therein; the portions of the overshoe bordering said orifices being provided with reinforcing means which is detachably attachable to said spikes, when the spikes are passed through said orifices, the orifices thus permitting penetration therethrough and projection therebelow of the said spikes.

ELLIOTT H. FEINBERG.
